UNITED STATES PATENT OFFICE.

PHILIP BLAIR FROST, OF SHEFFIELD, AND FREDERICK RINGS, OF LIVERPOOL,
ENGLAND.

COMPOSITE BEAM.

1,212,759.

Specification of Letters Patent. Patented Jan. 16, 1917.

Application filed May 25, 1915. Serial No. 30,280.

To all whom it may concern:

Be it known that we, PHILIP BLAIR FROST and FREDERICK RINGS, subjects of the King of Great Britain and Ireland, and residents, respectively, of Sheffield, in the county of York, and Liverpool, in the county of Lancaster, England, have invented certain new and useful Improvements in Composite Beams, of which the following is a specification.

This invention relates to improvements in the construction of beams which may be used by themselves for general structural purposes or in conjunction with the parts or materials hereinafter referred to to form an improved construction of floor, roof, bridge decking, road foundation, track, footpath, yard, area, quay and the like.

Our invention mainly consists in a beam of peculiar shape made of reinforced concrete, terra cotta or other suitable material applicable for use singly or side by side for various parts of structures such as those referred to, said beams being made by placing the concrete or other base material in molds together with the steel reinforcement to give it the required shape. The dimensions and the reinforcements will vary proportionately to the spans and loads to be dealt with.

The invention will be fully described with reference to the accompanying drawing in which—

Figure 1 is a perspective view of a beam constructed in accordance with our invention, indicating its external shape and the character of the reinforcement employed, Fig. 2 sectional elevation of a simple solid floor construction in which the beam shown in Fig. 1 is used, Fig. 3 a similar view of a hollow floor construction and Fig. 4 a sectional view indicating the application of the beam in a decking for bridges or the like and as a foundation for road and like tracks.

Referring to Fig. 1 the beam consists mainly of a compressive piece *a*, a web *b*, and a bottom member *c*, which latter serves as a cover to the tensile reinforcement and as a tension member distributing the loads over a given area and lugs or brackets *d*, providing against lateral bending, reinforced by rods in the shape of a hoop *h*, the lugs being required also for stability in handling the beams: *f* represents the tensile reinforcement, *e* the compressive reinforce-

ment and *g* the shear wiring secured by 55 means of clips *n* of any suitable construction to the top and bottom rods. As soon as the concrete has seasoned the beams are ready for use and can be placed in position without centering and are able to support 60 the load at once.

Fig. 2 illustrates a simple floor construction the ends of the beam resting on walls, girders, girder casings or any other suitable support. The spaces *k* may be filled 65 with a weak concrete such as coke breeze concrete and in that case floor boards can be nailed immediately to the concrete filling or cement, or wood block jointless flooring or any other floor finish can be applied 70 at once to the floor.

It will be readily appreciated that heretofore it was necessary to either cover a ferro concrete floor with a layer of coke breeze or wooden sleepers to receive the nails of the 75 floor boards and the present invention by doing away with that necessity effects a saving in cost and depth of construction. The necessity for a means of fixing over and above the floors as now used is due to the 80 fact that owing to the top layer of the floor slab or beam being under compressive stress the concrete of these parts has to be particularly hard and consequently does not allow of any nails being driven into it.

Fig. 3 illustrates a hollow floor construction, the advantages being that the floor is lighter and more sound proof. When applied for this purpose the lugs *d* are made square or flat at the top thus affording supports for a fillet *m* which may be of wood or coke breeze concrete or other suitable material into which nails can be readily driven to fix floor boards *o*. The construction is absolutely fire resisting, sound and vermin 95 proof.

Fig. 4 illustrates the application of the beam as a decking for bridges or the like and as a foundation for roads and the like tracks. In bridge construction the beams 100 are made and reinforced to the required depth and amount in order to resist the given loads for given spans and placed when matured side by side as shown, the ends resting on the abutments and the road filling material is placed immediately upon and between same as shown. For purposes of draining weep-holes can be readily ar-

ranged at the points of junction without detriment to the strength of the construction.

It is a well known fact that owing to depressions, ruts and other deformations under roadways the surface finish of the latter is likely to sink or crack. To obviate this a layer of concrete has been heretofore placed on the road foundation but owing to the fact that plain concrete has little resistance against tensile stresses this method proved unsatisfactory and steel rods were inserted so as to make the slab act as a beam over depressions. There are several objections to this method. Firstly, there can be no elasticity in such a slab and the impact of the traffic is not graduated unless a fairly thick layer of some elastic substance such as gravel is placed on the top of the concrete bed. Secondly, it is costly to arrange a solid road slab in such a fashion as to make access to pipes and sewers, &c., feasible. Thirdly, if reconstruction becomes necessary the whole of the bed has to be broken up and all the material and labor is wasted. To obviate these shortcomings beams of plain or reinforced concrete of square or rectangular section have been laid side by side but these beams still require a thick layer of filling for reasons stated above, and moreover are costly in material unless made hollow and in the latter case the cost of manufacture is high owing to the necessity of using a collapsible core in the casting. The present invention solves these difficulties completely. The beams are placed side by side and made of suitable length and strength the ends resting on transverse beams, walls or other rigid supports. Owing to the filling material entering between the beams to an appreciable extent the shock due to the impact of traffic is perfectly graduated and transmitted to a number of beams at the same time quite me-

chanically. The cost of production is reduced as the beams can be made between 45 shuttering without any core. The cross beams, walls or other supports aforesaid can be arranged so that proper trimmers are provided wherever access to drains, cables, watermains or other pipes is required and as 50 the beams are not substantially connected with one another it is easy to lift out any required number and replace them after repairs are done or any other purpose fulfilled.

In altering roads or reconstruction of 55 same the beams are simply lifted out and stacked near the site and can be used over again entirely. There is consequently no loss of material, and the cost of labor in forming the new road foundation is considerably 60 reduced.

Many other similar applications could be 65 enumerated but it is thought that the foregoing description fully bears out the application of the invention.

What we claim as our invention and desire to secure by Letters Patent is:—

A composite beam comprising a main portion of concrete material having a web, top and bottom members, and lugs which project laterally from the said parts, reinforcing rods extending longitudinally in the said top and bottom members, loops formed of rods and secured at intervals to the said longitudinal rods and holding them suitably 75 spaced apart and extending within the said lugs, and wires arranged diagonally and crosswise of each other and secured to certain of the rods in the top and bottom members and extending longitudinally in the 80 said web.

In witness whereof we have hereunto set our hands.

PHILIP BLAIR FROST.
FREDERICK RINGS.
